(57) **CLAIM**

The ornamental design for a cup holder tray for sofa, as shown and described.

DESCRIPTION

FIG. 1 is a perspective view of a cup holder tray for sofa showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the cup holder tray for sofa shown in an environment of use.

The broken lines shown in the drawings depict portions of the cup holder tray for sofa that form no part of the claimed design.

1 Claim, 8 Drawing Sheets
